UNITED STATES PATENT OFFICE.

FRANCIS C. SANDERS, OF POCATELLO, IDAHO, ASSIGNOR TO KAWNEER MANUFACTURING COMPANY, OF NILES, MICHIGAN, A CORPORATION OF MICHIGAN.

STORE-FRONT CONSTRUCTION.

1,371,442.

Specification of Letters Patent. Patented Mar. 15, 1921.

Application filed October 24, 1916. Serial No. 127,478.

To all whom it may concern:

Be it known that I, FRANCIS C. SANDERS, a citizen of the United States, residing at Pocatello, in the county of Bannock, in the 5 State of Idaho, have invented new and useful Improvements in Store-Front Constructions, of which the following is a specification.

This invention relates to store front constructions. It is an object of my invention to provide a new and improved bar for securing in place the edge of one or more panes of glass, and so designed that the retaining member may be quickly and readily 15 secured in place from the exterior.

It is a further object of my invention to provide a bar of this class with an improved finishing strip for covering the retaining means which can be readily and quickly 20 placed in position after the glass has been installed and the retaining members secured in place.

The above and other features of novelty, advantages and capabilities will become apparent from a detail description of the accompanying drawings in which I have illustrated a device embodying one form of my invention, but the construction there shown is to be understood as illustrative only, and 30 not as defining the limits of my invention.

Figure 1 is a perspective view of a corner bar embodying one form of my invention showing the finishing strip apart therefrom.

Fig. 2 is a vertical sectional view of the 35 same showing the finishing strip placed preparatory to being slid to its normal position.

Fig. 3 is a transverse sectional view of a slightly modified corner bar showing the finishing strip about to be placed.

Fig. 4 is a similar view showing the finishing strip in its normal position, and

Fig. 5 is a transverse sectional view of a division bar embodying one form of my invention.

While I have only illustrated my invention as applied to corner and division bars, it will be understood, of course, that it may be embodied in various forms of bars, for example, reverse angle bars and the like.

The bar consists of an inner retaining member 10 which is provided with resilient flanges 11 and an outer channel retaining member 12, provided with resilient flanges 13, the edges of the glass being held between 55 the resilient flanges 11 and 13 of the inner

and outer members in such a manner as to yield under abnormal pressure, and also to allow for the expansion and contraction of the glass. For securing the outer retaining member 12 to the inner members, 60 I provide a plurality of threaded screws 14, depending upon the length of the bar, which screws pass through openings in the channel of the outer retaining member and back through a non-rotatable nut 15 positioned 65 in the inner retaining member. It is obvious, however, that the non-rotatable nut may be omitted and the retaining screws 14 screwed directly into a screw-threaded opening in the inner retaining member. It 70 will thus be seen that the outer retaining member is secured in place from the outside, which is of great advantage, as the glass can be secured in place from the outside, and, too, as is frequently the case, it is extremely difficult, if not impossible, to tighten 75 the retaining screws or retaining means from the inside, for example, where the bar is positioned close to a supporting beam or girder 20, as shown in Fig. 4.

To provide a smooth outer surface and to cover the retaining means so that they will not be exposed to the weather, and thus subject to corrosion or rust, I provide a finishing strip 16, adapted to be readily placed 80 and moved to its normal position after the retaining members have been drawn up and the glass secured in place.

In the finishing strip shown it is substantially V-shaped in form with its inner edges 90 spaced apart and provided with a plurality of notches in one of its sides, the number of openings, of course, depending on the length of the bars. These openings are spaced apart so as to register with the retaining heads 17 secured in the channel of the outer retaining member, as shown in Figs. 1 and 2, while in the other three figures I have shown it as a part of the retaining screw for securing the outer and inner members together, in which case, I provide the retaining screw with a shoulder 18, adapted to engage the outer member in the depression of the channel 11. In either case whether I use the retaining head as a separate screw or the retaining head as a part of the retaining screw 14, the finishing strip 16 is first placed so that the apertures register with the retaining heads, as shown in Fig. 3, and the finishing strip is then turned 110

to the right in the particular illustration shown, until the retaining heads are completely within it, then it is slid downwardly or upwardly until the openings in the finishing strip have passed the retaining heads. It will thus be seen that I have provided an improved bar which resiliently holds the glass in place and allows for expansion and contraction, and in which the retaining means can be drawn up from the exterior, also an improved finishing strip which can be readily and quickly secured in place after the glass has been installed and the retaining members drawn up.

15 In installing my device the inner retaining member 10 is first positioned in place, the glass 19 is then positioned against the flanges 11, the outer channel retaining member 12 is then placed in position with 20 its flanges 13 against the glass, screws 14 are then placed in position and the inner and outer members drawn toward each other by rotating the screws in the proper direction by means of a screw driver or the 25 like until the edge of the glass is tightly gripped between the flanges 11 and 13. To complete the installation and present a neat appearance and protect the retaining screws from the weather, the finishing strip 16 is 30 then placed so that the openings register with the retaining heads 17 and then given a partial rotation either to the right or left, as the case may be, until the retaining edges are completely within it, then it is slid upwardly or downwardly, as the case may be, until the apertures pass the retaining head.

While I have described the particular form of my invention illustrated in the drawings as being applied to a store front, 40 it is, of course, obvious that it may be utilized in almost any construction for securing the edge or edges of the glass in place, for example, show cases and the like.

I claim:

45 1. In a device of the class described an inner glass retaining member, an outer glass retaining member, a headed fastening device connecting said glass retaining members for drawing said outer member toward 50 said inner member and operable from the exterior, a headed extension on said outer glass retaining member, and a slotted weather strip provided with an opening in one of its sides, connecting with the slot 55 whereby said opening may be passed over

said headed extension and the weather strip moved longitudinally to its final position.

2. In a device of the class described, an inner glass retaining member, an outer glass retaining member, headed fastening devices for drawing the outer member toward the inner member and a slotted weather strip provided with an opening in one of its sides connected with the slot, said opening permitting the strip to be applied in 65 position after said fastening devices have been tightened.

3. In a glass holding device, an outer glass retaining member, a slotted weather strip provided with an opening in one of its 70 sides, said opening being connected with the slot, and a headed fastening device secured to the outer retaining member whereby said headed device may be passed through said opening and into said slot to 75 permit said weather strip to be secured in position.

4. In a device of the class described, an inner glass retaining member, an outer glass retaining member, means for drawing the outer member toward the inner member, said means being operable from the exterior, a slotted weather strip provided with an opening in one of its sides and a headed fastening device secured to the 80 outer member and adapted to pass through 85 said opening and slot to hold the weather strip in position.

5. In a device of the class described, an inner glass retaining member, an outer glass retaining member, means operable 90 from the exterior for securing the two in place, a headed member secured to the outer glass retaining member and having its head spaced therefrom, a slotted weather strip 95 adapted to cover the exterior end of the headed member and securing means, one edge of said weather strip being provided with a notch, opening into the slot, so that the notch may be slipped over the headed member and then the weather strip moved longitudinally to lock the same in place.

In witness whereof, I hereunto subscribe my name to this specification in the presence of two witnesses.

FRANCIS C. SANDERS.
